Patented Oct. 7, 1919.

By *Geo. P. Kimmel*
Attorney

UNITED STATES PATENT OFFICE.

EUGENE F. PRATHER, OF EAGLETTE, ARKANSAS.

WRENCH.

1,318,175.

Specification of Letters Patent.

Patented Oct. 7, 1919.

Application filed June 6, 1918. Serial No. 238,515.

To all whom it may concern:

Be it known that I, EUGENE F. PRATHER, a citizen of the United States, residing at Eaglette, in the county of Dallas and State 5 of Arkansas, have invented certain new and useful Improvements in Wrenches, of which the following is a specification.

This invention relates to improvements in wrenches particularly to those types of wrenches employing means for permitting 10 quick and positive adjustment of the jaws thereof and it is the principal object of the invention to provide a wrench having a novel form of adjustment operable by the handle 15 whereby the movable jaw of the same, when adjusted, will be securely held against undue movement, but which, when desired, can be quickly released and moved to other positions.

20 Other objects will be in part obvious and in part pointed out hereinafter.

The improvements in the details and arrangement of parts will be apparent from an inspection of the accompanying drawings, when considered in connection with the 25 specific description hereinafter contained wherein a preferred embodiment of the invention is set forth.

In the drawings:

30 Figure 1 is a side elevation of the improved wrench having a part thereof broken away and shown in section.

Fig. 2 is a vertical transverse section there- 35 through taken on the line 2—2 of Fig. 1, and

Fig. 3 is a similar section taken on the line 3—3 of Fig. 1.

Having more particular reference to the drawings, in connection with which like 40 reference characters will designate corresponding parts throughout the several views, the improved wrench includes an adjustable jaw 1 having an opening 2 formed in one portion thereof in which a pawl 3 is ar- 45 ranged, for a purpose which will be sub- sequently described. Extending from the jaw 1 is a shank member 4, the outer end of which is curved and has connection with a handle member 5 by means of the loop 6 connected with the shank as at 7 and ex- 50 tending about a portion of said handle mem- ber.

A pivoted jaw 8 is provided and carries a shank 9, the outer side of which is provided 55 with a series of ratchet teeth 10, while the inner end of the same is connected to a yoke

11 as at 11^A, which yoke, as will be noted, passes about a portion of the shank 4 and is pivotally connected as at 12 to the inner end of the handle member 5, said end being 60 curved as at 5' to permit swinging movement of the shank 9.

In this connection, it is to be noted that the shank 9 passes through the opening 2 formed in the jaw 1 and has the various 65 ratchet teeth formed thereon positioned for engagement with the pawl 3 carried by the adjustable jaw adjacent said opening 2.

In using my improved wrench, to adjust the jaw 1 with relation to the jaw 8, the 70 latter is swung upon its axis 11^A thereby disengaging the ratchet 10 carried by the shank 9 from the pawl 3, thus permitting sliding movement of the shank 4 and the jaw 1 ar- 75 ranged thereon. When the jaws have been properly positioned, the adjacent ratchet tooth is engaged with the pawl 3 and the jaws applied to the object in such manner that the turning movement of the jaws tends 80 with the ratchet teeth.

Manifestly the construction shown is capable of considerable modification and such modification as is within the scope of my claims, I consider within the spirit of 85 my invention.

I claim:

1. A wrench including an adjustable jaw having an opening therein, a pawl formed on the wall of said opening, a shank ex- 90 tending from the jaw, a pivoted jaw ar- ranged adjacent the adjustable jaw, a shank carried by the pivoted jaw extending through the opening in the movable jaw, ratchet teeth carried by the shank of the 95 pivoted jaw arranged to coact with the pawl and prevent separation of the jaws when the latter are engaged and turned in one direc- tion upon an object, turning movement of the jaws in the opposite direction tending to 100 disengage the pawl from the teeth and permit relative adjustment of the jaws, a handle member having one terminal engaged between the shanks, a yoke pivotally receiving the second shank, secured to the terminal 105 of the handle and slidably receiving the adjustable jaw shank, and means carried by the adjustable jaw shank and engaging the handle for guiding the movement of the adjustable jaw.

2. A wrench including an adjustable jaw having an opening therein, a pawl formed on

the wall of said opening, a shank extending from the jaw, a pivoted jaw arranged adjacent the adjustable jaw, a shank carried by the pivoted jaw extending through said opening, ratchet teeth carried by the shank of the pivoted jaw and arranged to coact with said pawl and prevent separation of the jaws when the latter are engaged and turned in one direction upon an object, 5 turning movement of the jaws in the opposite direction tending to disengage the pawl from the teeth and permit adjustment of the adjustable jaw, a handle member hav-

ing the inner terminal curved to permit swinging movement of the pivoted jaw and 15 arranged between the adjacent terminals of the jaw shanks, a yoke secured to the handle, arranged about the shanks and pivotally engaged with the shank of the pivoted jaw, and a loop connected to the outer end of the 20 first mentioned shank and engaged about the handle.

In testimony whereof I affix my signature hereto.

EUGENE F. PRATHER.
